UNITED STATES PATENT OFFICE

JEAN MELLANDER, OF BRUSSELS, BELGIUM

PROPELLER FOR HELICOPTEROUS AIRCRAFT

Application filed November 23, 1925, Serial No. 70,983, and in Belgium November 28, 1924.

The invention relates to propellers for helicopters and specially to those in which the propeller is situated above the body and constitutes: (1) a new way of obtaining such an air pressure under the propeller blades that simultaneously with the ascensional power a propelling force shall be induced. (2) The new method to use this propelling force to retain the propeller shaft upright, 10 or to redress it, when tilted. (3) To obtain by this new method a state of stable equilibrium.

The drawings show graphically in Fig. 1 a horizontal propeller with the blades inclined; Fig. 2 an inclined propeller; Fig. 3 a propeller with a movement for inclining the blades radially; Fig. 4 a propeller with a movement for obtaining a stable equilibrium and Fig. 5 shows a realized propeller.

20 The new way of obtaining the propelling force consists in the fact, that the blades, without any tilting of the propeller shaft, can be inclined in the radial sense to the horizontal, exactly as if the propeller shaft 25 had been tilted. See drawings, Figures 1 and 2.

This radial inclining of the blades is obtained in the following manner, that each blade oscillates on a geometrical transversal axis, this ideal axis passing horizontally through the air pressure centre under the blade, and that, during each revolution of the propeller, the blades can be forced, by suitable means, to vary this radial inclina- 35 tion, between zero and a maximum desired.

There will be several ways of inclining the blades e. g. a method resembling those already used by different helicopters, for varying the incidence angle. Fig. 3 of the drawings shows graphically a new method, consisting in this, that every blade 2, oscillating on a transversal axis 3, at a certain distance from the propeller axis 1, in a point 4, at a certain distance from the oscillating axis 3, 45 is connected by means of an articulated link 5, with one arm 6 of the knee lever 7, having its centre of oscillation 8 most favorably coinciding with the common centre of rotation of the air pressure centres under the 50 blades and having the end of its other arm

9, rotating on a bearing 10, supported by, and its position controlled by a lever 11, having its oscillating centre 12, on the body of the aircraft itself, thus enabling, by means of the lever 11, the arm 9 of the knee lever, 55 to rotate round a geometrical axis, at a certain inclination to the propeller axis, thus forcing opposite blades to incline radially in the same sense, and, during every revolution of the propeller, to vary their radial inclination between zero and a maximum desired, 60 imparting simultaneously to the blades an ascensional power 13 and a propelling force 14.

Fig. 4 of the drawings shows a scheme, 65 giving to the propeller a state of stable equilibrium around its tilting centre 12, thus obtained at first by a weight 14', attached to an arm 18, connected with the lever 11, having its oscillating centre most favorably coinciding with the tilting centre of the propeller shaft, at a certain distance under the centre of oscillation 12, thus forcing lever 11, in spite of the movements of the aircraft, by gravitation only, to retain approximately 70 the same position to the horizontal, and secondly by giving the levers 6, 9 and 11, such lengths, that the blades incline quicker than the propeller axis, to the horizontal, when the propeller axis, by the gliding of the propeller head, due to exterior forces, inclines to one or other direction, thus increasing the propelling force 14, in proportion to the gliding 75 of the propeller head, until it neutralizes the exterior forces and brings back the propeller head to its normal position, above the body of the aircraft, as soon as the exterior forces have ceased to operate.

Figure 5 of the drawings shows one of the ways of constructing such a propeller. The propeller shaft 1 can be rotated in any known manner, either directly in bearings, or by means of a universal joint, and to tilt around a geometrical point 21, this, in the first case, being most favorably coinciding with the centre of resistance of the aircraft body, and in the second case with the centre of the universal joint. The hollow shaft 1 carries the ring 4, by means of the wires 2 and 3, and this ring carries the blades 6, by means of the 100

little arms 5, and the pivots in the points 7. The knee lever is composed of the arm 8, oscillating at the ball pivot 9, fixed to the shaft, supplied with the little arms 11, passing through suitable holes in the shaft, carrying the circular element 12 and this the ring 13, by means of the wires 14 and 15. This ring is connected with the blades at the points 17, by means of the articulated links 16. The end 10 of the arm 8 rotates on the bearing 18, carried by lever 20, by means of the articulation 19, having its oscillating centre 21 coinciding with the tilting centre of the propeller shaft, on an arm 22, fixed on the aircraft body and sticking up in the hollow shaft. Lever 20 is supplied with the arm 23, and this carries a weight 24. The levers 20 and 8 and the radius of the ring 13, are of such lengths, that the blades incline quicker than the propeller axis to the horizontal.

Figure 6 of the drawings shows another method of construction having a solid shaft 1, whilst the circular element 12 is directly oscillating on the ball 9, fixed to the shaft. This circular element is supplied with two or more arms 10, rotating together on the ball-bearing 18, and this, by means of the articulated link 19, is connected with the lever 20, having its oscillating centre 21 on an arm 22, fixed to the aircraft body.

I claim as new:

1. Propellers for helicopters comprising a shaft, a mounting on said shaft comprising radial arms for carrying the blades, blades mounted movable to oscillate on axes transverse to said arms and means for controlling the radial inclination of the blades.

2. Propellers for helicopters comprising a shaft, a mounting on said shaft comprising radial arms for carrying the blades, blades mounted movable to oscillate on axes transverse to said arms, the knee lever connected with the blades and means for controlling the position of this lever and thus the radial inclination of the blades.

3. Propellers for helicopters comprising a shaft, a mounting on said shaft comprising radial arms for carrying the blades, blades mounted movable to oscillate on axes transverse to said arms, the knee lever connected with the blades and with another lever, having its position controlled by a weight.

JEAN MELLANDER.
